W. E. WHITE

JUNCTION CLIP AND SPACER FOR REINFORCEMENTS

Filed Dec. 6, 1926

UNITED STATES PATENT OFFICE.

WILLIAM E. WHITE, OF CHICAGO, ILLINOIS, ASSIGNOR TO KALMAN STEEL COMPANY, OF CHICAGO, ILLINOIS, A CORPORATION OF DELAWARE.

JUNCTION CLIP AND SPACER FOR REINFORCEMENTS.

Application filed December 6, 1926. Serial No. 152,893.

My invention relates to concrete reinforcement, and particularly to means for engaging and holding crossed bars and for spacing apart a double series of such bars.

5 The invention comprises essentially a rigid spacing element preferably composed of sheet metal or similar material, together with a pair of spring arms secured at one end of the spacer and adapted to pass over one 10 crossed bar and to be hooked around over a parallel crossed bar in the adjacent series.

The foremost object in the proposed construction is to simplify the steps of manufacture and installation and to assure rigidity 15 and firmness in the performance of the required duties.

The invention will be more readily understood by reference to the accompanying drawings, in which;

20 Fig. 1 is an elevation partly in section showing a pair of devices constructed in accordance with my invention, the two devices varying somewhat in one feature;

Fig. 2 is a sectional view on the line 2—2 25 of Fig. 1;

Fig. 3 is an end view of the device shown at the left hand part of Fig. 1, and;

Fig. 4 is a plan view of the construction shown in Fig. 3;

30 In the drawings, I have shown parallel spaced apart bars or rods A—B and parallel, right-angularly disposed rods or bars C—D. It is intended when installing the reinforcement in roadways to assemble a 35 unit such as shown in Fig. 1, and then to lift the assembly and place it in position on the prepared roadway ready for the pouring of the concrete. In the event that no means are provided for retaining the reinforcing 40 unit in spaced relation above the soil, it is customary to pour a layer of concrete then to place the reinforcement thereon, and then pour the remainder of the slab. I have, however, provided in the device here disclosed, 45 means for spacing the unit above the soil so that the reinforcement may be assembled and placed in position before any pouring is done. This reduces the labor cost and enables the complete pouring of a slab in one 50 operation. A device for accomplishing that result is shown at the left hand portion of Fig. 1, and in Fig. 3.

The device illustrated at the right hand end of Fig. 1 comprises a sheet metal spac-

ing element having a central rib, 10, and side 55 flanges, 11. The upper end of the member is cut diagonally to provide a deep seat for the bar B, while at the lower end a V-shaped notch, 10^a, is cut in the rib, 10 and the overhanging portion 10^b is bent backwardly until 60 the flanges 13, are in contact with the flanges, 11. This provides a broad and deep seat for the bar A, and insures rigidity and stability 65 of the structure. At the upper end, the flanges 11 are extended and bent over, as at 12, to overlie the crossed bar C. This serves as a means for holding the bar against movement in two directions. At the lower end, the flanges 13, at the bend therein constitute 70 the fastening means for the horizontal portions, 14 of the spring arms, 15. The upper ends of the arms are rebent to provide hooks, 16, adapted to be sprung over the bar C. The connecting portion between the two 75 arms, 15, is bent in the form of a loop, 17, angularly disposed relative to the portions, 14, and adapted to overlie the bars A, the curved end portions, 18 of the spring arms 80 overlying the bars D. Before installation, the spring arms, occupy a position similar to that indicated by the dotted lines at the right hand end of Fig. 1. After being placed in position, the arms are swung upwardly into the full line position.

In the construction shown at the left 85 hand end of Fig. 1, and in Figs. 3 and 4, the parts just described are identical, and no further description is considered necessary. However, the flanges, 11 are extended laterally and downwardly to form legs, 19, the 90 ends of which are extended horizontally to form feet, 20. The length of the legs is such that the reinforcing unit after having been assembled, may be lifted and placed in position on the prepared soil, beneath the 95 proposed roadway, and the entire slab of concrete be poured. It may be found sufficient to employ the device shown in Fig. 3 at some of the intersections, the remainder of the intersections being held by the device 100 shown at the right hand end of Fig. 1, or all of the devices may be as shown in Fig. 3.

The practical advantage of the spacing and holding device will be apparent to those accustomed to the use of such articles; the 105 assembly of a reinforcing unit may be very quickly and conveniently accomplished, without the use of special tools, and without the

use of separated or separable parts. The construction is of extremely simple form and may be economically constructed.

Modifications in the form and arrangement of parts may be made without departure from the spirit of my invention.

I claim:

1. In combination, a sheet metal spacer having a rib and providing a seat for a bar at each end, and a spring arm pivoted at one end of said spacer and adapted to overlie a crossed bar near its pivot end and to hook over a second crossed bar at the opposite end of the spacer.
2. In a device of the class described, the combination of a rigid member providing a seat at each end for parallel spaced bars, and means for holding spaced parallel crossed bars said means including a spring arm adapted to be bent around one of said crossed bars and to hook over a spaced crossed bar.
3. In combination, a sheet metal spacing member providing a seat at each end for a bar, the seat at one end being relatively wide whereby to insure stability, a spring arm fastened to the sheet metal member at one end and adapted to be bent over a crossed bar at a point near that at which said arm is connected to the member, said arm having a hooked end adapted to be sprung around a spaced bar at the opposite end of said member.

4. In combination, a sheet metal spacing member having a rib and flanges, said member providing a seat at each end for spaced parallel bars, the flanges at one end being projected beyond the rib to overlie a crossed bar, a spring arm connected to the member at one end and adapted to engage a crossed bar and to be hooked around a crossed bar at the opposite end at the point at which said last named crossed bar underlies said projected flanges.

5. In combination, a rigid sheet metal spacing and supporting member having a rib and a side flange, the rib of said member being notched near one end, the overhanging portion being bent backward until the flanges are in contact, thereby providing a deep, wide seat for a bar, the flanges at the opposite end of the member being projected and bent to overlie a bar, and a spring arm connected to the member at one end and adapted to be bent and hooked around a crossed bar at the opposite end of the member.

6. In combination, a rigid, sheet metal spacer providing a seat at each end for a bar, and a pair of spring arms pivoted to one end of said spacer and adapted to engage over a bar at the pivot end and to be hooked over a parallel bar at the opposite end of said spacer.

In testimony whereof I have affixed my signature.

WILLIAM E. WHITE.
